UNITED STATES PATENT OFFICE.

TIMOTHY G. OWENS, OF DUPUYER, MONTANA, ASSIGNOR OF ONE-HALF TO JOHN F. HUGHES, OF SHELBY, MONTANA.

STEEL-PUNCH.

No. 917,739.

Specification of Letters Patent.

Patented April 6, 1909.

Application filed May 16, 1907. Serial No. 373,953.

To all whom it may concern:

Be it known that I, TIMOTHY G. OWENS, a citizen of the United States, residing at Dupuyer, in the county of Teton, State of Montana, have invented certain new and useful Improvements in Steel-Punches; and I do hereby declare the following to be a full, clear, and exact description of the invention, such as will enable others skilled in the art 16 to which it appertains to make and use the same.

This invention has relation to that class or kind of punches that are adapted to punch holes in iron or steel plates or other kinds or 15 forms of metal, and that comprise a die and punch proper, the latter being adapted to be operated by percussion or pressure.

It is the object of the invention to provide improvements that will enhance the facility 20 and accuracy with which the punch may be employed, as well as to simplify its construction to the utmost in view of the scope of the work it is capable of performing.

The nature of the invention is fully and 25 clearly ascertainable from the device portrayed in the annexed drawings, forming a part of this specification, in view of which it will first be described with respect to its construction and mode of operation and then be 30 pointed out in the subjoined claim.

Of the said drawings—Figure 1 is a perspective view of the punch complete, showing how it may be held in the hand and be set 35 to punch bolt, rivet or other holes through a metal work piece. Fig. 2 is an enlarged vertical section taken on the line 2, 2, Fig. 1. Fig. 3 is a plan of the die. Fig. 4 is a perspective view of the punch separated from the machine. Fig. 5 is a plan of the front end of 40 the rocking lever that carries the punch.

Similar characters of reference designate similar parts or features, as the case may be, wherever they occur.

As is indicated in the drawings, the frame 45 of the punching device comprises a base A and an overhanging arm B, the said two parts being integrally connected at what may be considered their rear ends by an integral bow or bend C to form a U-shaped frame. 50 The base A is provided at its forward end with a terminal enlargement, forming a die socket 1 adapted to receive the die D having a hole 2 formed through its center. The overhanging arm B is coextensive with the 55 base, and is provided at its forward end with

a terminal enlargement forming a guide-head 3 having a vertical aperture formed therethrough, in which the shank or body 4 of the punch E is held. The said punch is arranged in the guide-head so as to be in exact alinement with the hole 2 in the die D. Moreover, the hole in the die is of the same form in cross section as the punch considered in the same way; that is if the former is round the latter will be also, and if the former should be 65 square or triangular the latter will conform thereto.

The punch E while made to fit the hole in the die will be so formed as to move easily therein.

The base and overhanging arm will be of such length as may be required to permit metal plates or other pieces of metal to be arranged between them so that a hole or holes can be punched therethrough at the 75 proper point or points. The base member is also constructed to be supported on an anvil (not shown) or on a suitable block or bench. In the two latter instances a bench-plate (not shown), well known in the art, may be employed for the immediate support of the base member, which has a vertical tang as shown in Fig. 1 to fit in the hole in the anvil or bench-base. The socket and guide forming enlargements, are positioned proximal to one 80 another.

L designates a rock lever, fulcrumed by means of a depending lug, to the upstanding stud 6 on the upper side of the overhanging arm said lever having at one end a handle 90 termination to be pressed upon by the thumb in setting and releasing the punch. The forward end of the lever L is bowed and forked and its terminals are provided with integral pins 7, 7 extending inward toward 95 each other; and as the prongs or tines 8, 8 of the fork are resilient, the ends may be sprung apart and released to cause the pins 7 to engage the rounded sockets 9, 9 formed in the sides of the body 4 of the punch E.

A spring s is arranged between the upper surface of the overhanging arm B and the lower surface of the rear portion of the lever L and operating with a tendency to press the forward end of the lever carrying the punch body provided with the punch E down toward or upon the die D, this movement being permitted by means of the resilient prongs 105 8, 8, and the rocking movement imparted to this lever L, by means of the depending se- 110

curing lug. The punch-body and punch are raised by the pressure of the thumb on the rear end of the rear arm of the lever as stated.

5 The lower or operating end of the punch is provided centrally with a point *p* which is adapted to be set upon the mark made for the center of the hole to be punched, so that the punch will not only be centered but will 10 be guided straight through the material, punching out a plug that will pass directly through the hole in the die.

10 The die D and punch body 4 are made removable so that punches and dies, or dies 15 having holes of different size and shape may be employed.

Supposing the parts to be assembled as shown in Fig. 1, a plate of steel or iron, marked or dotted at the points where holes 20 are to be punched therethrough, will be placed on the die the punch having been previously raised, the work piece being moved so as to center the point of the punch on the mark, when by the release of the lever L the 25 punch will be set upon the material and by a blow of a sledge-hammer, or lighter striking tool upon the top of the punch-body, the punch 4 will cut a hole through the material, forcing the plug cut out through the hole in 30 the die. The work done under the described circumstances will be perfect. The hole formed through the material will have clean cut sides and scarcely a perceptible fin on the under surface.

35 When a die of different size or form is to be used, the one in the base can be lifted out and

the desired die substituted for it. The same can be done with the punch-body provided with a punch corresponding to the hole in the die. By springing apart the prongs on the 40 end of the forward arm of the lever L, the punch body can be released and another put in its place.

The punch is adapted to be used in the manufacture of cutlery, or in machine shops 45 to punch rivet or bolt holes through plates of metal, or in blacksmith shops or shops on farms, and elsewhere. Its simplicity, ease of operation, and the low cost at which it may be produced commend it for use wherever 50 a relatively small metal punch may be required.

What is claimed is—

A U-shaped frame having two terminal enlargements one forming a guide head and 55 the other a die socket, these enlargements being positioned proximal to one another, a die within said socket, a punch slidably held within said guide head, an upstanding stud carried by said frame along the upper edge, a 60 rocking lever held by said stud having its forward end forked to provide two bowed resilient prongs ending in inward extending pins, said pins being in engagement with said punch, and a spring interposed between said 65 frame and lever, all arranged as set forth.

In testimony whereof, I affix my signature, in presence of two witnesses.

TIMOTHY G. OWENS.
